DOOR BOTTOM CLOSING AND SEALING DEVICE

Wilhelm A. Beck, Merion, Pa.

Application May 25, 1943, Serial No. 488,409

6 Claims. (Cl. 20—68)

1

This invention relates to a novel device for closing the space beneath a door, the said device being of the type employing a closure member which is moved automatically to its operative and inoperative positions in response to closing and opening of the door with which the device is associated. The present application is a continuation in part of a copending application Serial No. 471,160, filed January 2, 1943 and subsequently abandoned.

The principal object of this invention is to provide an extremely simple device which is inexpensive to manufacture and easy to install, and which is highly efficient in the performance of its intended function.

Another object of the invention is to provide a device of the above-mentioned character employing a minimum number of parts, which does not require a high degree of accuracy in manufacture and yet is highly efficient in effecting a tight seal to prevent passage of air beneath a door when the latter is closed.

A further object of the invention is to provide a device of this character which, by virtue of its construction, operates in a manner to eliminate any possibility of a carpet or rug near the door interfering with the operation.

Other objects and features of the invention will be apparent hereinafter.

In the accompanying drawing:

Fig. 1 is a perspective view of the lower portion of a door and associated door frame with the device of the invention mounted thereon;

Fig. 2 is a rear face view of the device before mounting on the door looking in the direction of arrows 2—2 of Fig. 1;

Fig. 3 is a similar view of the device mounted on the door, taken in the direction of the said arrows in Fig. 1 and showing the initial action which takes place during closing of the door;

Fig. 4 is a similar view showing the device in its fully operated position with the door fully closed;

Fig. 5 is an enlarged sectional view of the device in its inoperative condition;

Fig. 6 is an enlarged sectional view taken along line 6—6 of Fig. 4 and showing the sealing action of the device;

Fig. 7 is a perspective view of a clip employed to suspend the closure member; and

Fig. 8 is a perspective view of a supporting and guide member employed in the device.

Referring more particularly to the drawing, in Fig. 1 there is shown the lower portion 1 of a door which is hinged at one side, as shown at 2,

and having an associated door frame 3. During closing movement, the door moves in the direction of the arrow 4, and, in the figure, it is shown just prior to reaching its fully closed position. The purpose of this showing will appear presently.

According to the present invention, there is provided a member 5, preferably formed of wood, having provision for fixed attachment to the door, for example, by means of attachment screws 6. The member 5 is shaped in cross-section as shown in Fig. 5, and forms with the lower portion of the door an inverted channel 7 of predetermined width having parallel vertical walls 8 and 9. A resilient flexible rod 10 (Figs. 2 to 4) of predetermined fixed length, preferably formed of metal, is disposed in the channel 7 and has one end affixed to member 5 and door 1, as shown at 11, and has its other end slidably supported by an element 12 and projecting beyond member 5 at the hinged edge of the door for engagement with the head of a screw 13 carried by the door frame. Preferably, the fixed end of the rod 10 is bent about the shank of an anchoring screw in the manner illustrated.

Also disposed in channel 7 is a flat closure strip 14, preferably formed of wood, which is suspended from rod 10 by means of an element 15. The strip 14 is of rectangular cross-section, as shown in Fig. 5, and is substantially smaller in thickness than the width of the channel 7 so that the strip is loosely disposed in the channel. The strip is rigidly attached to the rod 10 by means of element 15 at a single point offset from the center of the rod toward the unhinged edge of the door, as clearly shown in Figs. 2 to 4. Except for its suspension from rod 10 at the single point mentioned, the strip 14 is entirely free, there being no guide or restraining members associated with the strip, such as are found in many devices of this general type. In its normal position, as shown in Fig. 2, the strip 14 is slightly offset longitudinally with respect to the fixed member 5, the reason for which will appear presently. Also, in its normal position, the strip abuts against the bent or curled end of rod 10 and against the lower part of supporting element 12 so that the rod 10 is normally slightly bowed and has some initial tension, it being noted that the bent or curled end of rod 10 and the lowermost end of the supporting element 12 act as stops to limit the upward movement of the strip 14.

The elements 12 and 15 are preferably formed as shown in Figs. 7 and 8. Element 15 is a sim-

ple metal clip having turned-out pointed projections 16 which are adapted to bite into the opposite sides of strip 14. When in place, this clip snugly embraces the rod 10 and provides a fixed point of attachment between the rod and the strip 14.

Element 12 is shaped as shown in Fig. 8 and has turned-out pointed projections 17 which bite into member 5 to secure the said element in fixed position on said member. It will be seen that element 12 has an inclined surface 18 which is disposed in the channel 7 in cooperative relation with the free end of rod 10. This end of the rod is slidably retained between the upper wall 19 of the channel 7 and the upper edge of the inclined surface 18 on element 12, which upper edge constitutes a line contact support or bearing for said end of said rod.

By reason of the construction of the device, as hereinbefore described, the closure strip 14 has complete freedom of movement and the device operates in a novel manner to insure complete freedom from interference with any nearby rug or other object and also to effect a simple airtight seal. Considering the operation of the device, when the door is open, the projecting end of rod 10 is free of engagement with the screw 13, and closure strip 14 is in its fully raised inoperative position, as shown in Fig. 2. When the door is closed, certain movements of the strip 14 take place in prearranged sequence. When the free end of rod 10 first engages the head of screw 13, the strip 14 moves to the position shown in Figs. 1 and 3, particularly the latter. It will be noted that the strip has been moved longitudinally and that the end of the strip adjacent to the hinged edge of the door has been lowered into engagement with the floor, represented at 20, while the opposite end of the strip is still in raised position. This action is due to the position of the point of suspension of the strip on the rod. During this initial movement of the strip, the fixed bent end of the rod 10 serves as a fulcrum, and the movement of the strip 14 is substantially that of a simple lever.

As the door is moved to its fully closed position, the further flexing of the rod 10 causes the strip 14 to move to its fully operative position, as shown in Fig. 4. However, during this latter movement, the strip 14 is tilted or rotated about its longitudinal axis into the position shown in Fig. 6, by reason of the initial engagement of the strip with the floor 20 and the loose disposition of the strip within channel 7. In its tilted position, the strip effects a sealing engagement with the walls of channel 7, thus preventing the flow of any air around the strip 14. It will also be noted that the strip effects an edge contact with the floor 20 to provide a tight seal therewith. Thus, the loose and free disposition of the strip 14 in the relatively large channel 7, together with the initial lowering of the strip into engagement with the floor, accomplishes the novel sealing action just described.

When the door is opened, the reverse sequence of actions takes place. The end of strip 14 nearest the unhinged edge of the door first rises from the floor to the position shown in Fig. 3, and then the rest of the strip rises to the fully inoperative position of Fig. 2.

The movements of the strip during both closing and opening of the door prevent any interference with the operation by a carpet or rug which may extend close to the position of the closed door. Since the end of strip 14 adjacent

the unhinged edge of the door is not lowered, during closing of the door, until the door has practically reached its fully closed position, and since the said end of the strip is immediately raised upon initial opening movement of the door, there can be no interference with any carpet or rug in the immediate vicinity of the door. Moreover, since the rod 10 is normally under some initial tension, the device is quick-acting and this further insures against any interference with a close-by rug or carpet.

From the foregoing discussion, the reason for the normal, longitudinal, offset position of strip 14 with respect to member 5, as shown in Fig. 2, will now be apparent. Owing to the manner in which the strip is moved, there is a tendency for it to move slightly in a longitudinal direction. By having the strip normally offset slightly in a longitudinal direction, it is caused to align itself with member 5 and the lower portion of the door when moved to operative position, as shown in Fig. 4.

The use of a rod 10 of fixed length in conjunction with the simple screw 13 simplifies the structure and, at the same time, affords a substantial range of adjustment. By reason of the construction of the device, a very slight movement of screw 13 inward or outward effects a substantial adjustment in the position of the closure strip 14 when it is in operative position. In this manner, the device may be adjusted to effect proper closure of the space beneath a particular door. Moreover, there is no possibility of the device getting out of adjustment.

The structure of the supporting and retaining element 12 is also an important feature of the device. During initial closing of the door, as shown in Fig. 3, the free end portion of rod 10 engages the uppermost, inner edge of the inclined surface 18 on element 12 which acts as a line contact support or bearing for the free end portion of rod 10 and also acts somewhat as a fulcrum. Upon further door-closing operation, the end of the rod in engagement with the head of screw 13 rises slightly and the end portion of the rod is elevated above portion 18 of element 12. The downwardly inclined surface 18 permits downward flexing of the rod 10 without engagement with said surface. Thus, the structure of element 12 permits a maximum degree of freedom of movement of the free end of the rod 10 and prevents wear due to friction, friction being reduced to a minimum by virtue of the line contact between the uppermost inner edge of the inclined surface 18 and the free end of the rod 10.

From the foregoing description, it will be seen that the invention provides a device which embodies a minimum number of simple parts which may be readily manufactured and assembled and which are so constructed and arranged as to produce the desired actions above described. The device does not require a high degree of precision in the making of its parts; in fact, the loose disposition of the closure strip 14 within the channel 7 eliminates any need of accuracy of formation of the members 5 and 14. Moreover, the rod 10 is simply cut to a desired length and assembled with the other elements. The construction of elements 12 and 15 merely involves simple cutting and stamping of sheet metal blanks.

The device is entirely devoid of any guides or restraining elements which would tend to complicate the structure and would also tend to interfere with the free movement of the closure strip. Moreover, there is substantially no wear

due to friction between the parts. A device constructed in accordance with the invention has been subjected to a life test, and thus far it has operated over 365,000 times without any perceptible wear of its parts. It is to be noted further that warping of a door will not interfere with the operation of the device, since the loose disposition of the closure strip in its channel insures against any binding tendency.

With the parts 5 and 14 formed of wood or other easily cut material, the device may be readily cut to fit a particular sized door. As illustrated, the device is of a width to fit a standard sized door. However, by extending the parts 5 and 14 substantially beyond the anchorage point 11 of the fixed end of the rod 10, the device may be readily adapted for larger sized doors. The user may then cut off any excess so as to adapt the device for a particular door size. Moreover, the closure strip 14 can be scribed and cut to fit any irregularity of the floor.

It will be understood, of course, that the invention is not limited to the specific form illustrated, but is capable of various modifications and embodiments within the scope of the appended claims.

I claim:

1. In a device of the class described, means for forming at the bottom of a side-hinged door an inverted channel extending the width of the door, said channel having parallel vertical walls, a flexible rod disposed in said channel having one end affixed therein and having its other end projecting beyond said channel at the hinged edge of the door for engagement with the door frame, a support for the said other end of the rod including a flat, inclined bottom surface, said surface extending from a location adjacent the hinged edge of the door and being inclined downwardly therefrom toward the center of the rod, the upper inner edge at the top of said surface forming a line contact support for the said other end of said rod, a flat strip of rectangular cross-section disposed in said channel and movable longitudinally and vertically therein to close the space beneath the door when the latter is closed, and means suspending said strip from said rod at a point offset from the center of the rod toward the unhinged edge of the door, whereby the end of the strip adjacent the hinged edge of the door is moved longitudinally and is initially lowered and the rest of the strip is subsequently lowered as the door is moved to closed position.

2. In a device of the class described, means for forming at the bottom of a side-hinged door an inverted channel extending the width of the door, said channel having parallel vertical walls, a flexible rod disposed in said channel having one end affixed therein and having its other end projecting beyond said channel at the hinged edge of the door for engagement with the door frame, a support for the said other end of the rod including a flat inclined bottom surface, said surface extending from a location adjacent the hinged edge of the door and being inclined downwardly therefrom toward the center of the rod, a flat strip of rectangular cross-section disposed in said channel and beneath said inclined surface of said support and movable longitudinally and vertically within said channel to close the space beneath the door when the latter is closed, the upper inner edge at the top of said inclined surface of said support forming a line contact support for the said other end of said rod, and the lower outer edge at the bottom of said inclined

surface of said support constituting a stop for engagement by the upper edge of said strip to limit upward movement of said strip within said channel, and means suspending said strip from said rod at a point offset from the center of the rod toward the unhinged edge of the door, whereby the end of the strip adjacent the hinged edge of the door is moved longitudinally and is initially lowered and the rest of the strip is subsequently lowered as the door is moved to closed position.

3. A device for closing the space beneath a side-hinged door when the latter is closed, comprising means for forming at the lower portion of the door an inverted open-ended channel of substantial width, said channel extending the width of the door, a flexible rod substantially entirely disposed in said channel having one end affixed therein and having its other end slidably supported and projecting from the end of said channel at the hinged side of said door, the projecting end of said rod being engageable by the door frame to bow the rod downwardly when the door is closed, said rod being supported only at its ends so that it is freely disposed in said channel for flexing movement, a closure strip disposed in said channel and being of substantially smaller thickness than the width of said channel so as to be freely movable therein, and means suspending said strip from said rod at a point offset from the center of the rod so as to effect initial lowering of the end of the strip at the hinged side of the door, said closure strip in its normal raised position being offset longitudinally with respect to said channel and projecting slightly therefrom at the hinged side of the door, and being moved longitudinally from its offset position into alignment with said channel during the lowering movement.

4. A device for closing the space beneath a side-hinged door when the latter is closed, comprising a member adapted to be attached to the lower portion of the door and extending crosswise of the door when attached thereto, said member having a securing portion extending longitudinally of the member and constituting the upper part thereof, and also having a relatively thin depending portion which forms with the lower part of the door an inverted open-ended channel of substantial width, a flexible rod substantially entirely disposed in said channel having one end affixed therein and having its other end slidably supported and projecting from the end of said channel at the hinged side of said door, the projecting end of said rod being engageable by the door frame to bow the rod downwardly when the door is closed, said rod being supported only at its ends so that it is freely disposed in said channel for flexing movement, a closure strip disposed in said channel and being of substantially smaller thickness than the width of said channel so as to be freely movable therein, and means suspending said strip from said rod at a point offset from the center of the rod so as to effect initial lowering of the end of the strip at the hinged side of the door, said closure strip in its normal raised position being offset longitudinally with respect to said channel and projecting slightly therefrom at the hinged side of the door, and being moved longitudinally from its offset position into alignment with said channel during the lowering movement.

5. A device for closing the space beneath a side-hinged door when the latter is closed, comprising a wooden strip of substantial overall

thickness adapted to be attached to the lower portion of the door and extending crosswise of the door when attached thereto, said strip being cut away so as to form with the lower part of the door an inverted open-ended channel of substantial width, a flexible metal rod substantially entirely disposed in said channel having one end affixed therein and having its other end slidably supported and projecting from the end of said channel at the hinged side of said door, the projecting end of said rod being engageable by the door frame to bow the rod downwardly when the door is closed, said rod being supported only at its ends so that it is freely disposed in said channel for flexing movement, a wooden closure strip disposed in said channel and being of substantially smaller thickness than the width of said channel so as to be freely movable therein, and means suspending said closure strip from said rod at a point offset from the center of the rod so as to effect initial lowering of the end of the closure strip at the hinged side of the door, said closure strip in its normal raised position being offset longitudinally with respect to said channel and projecting slightly therefrom at the hinged side of the door, and being moved longitudinally from its offset position into alignment with said channel during the lowering movement.

6. In a device of the class described, means for forming at the bottom of a side-hinged door an inverted channel extending the width of the door, a flexible rod disposed in said channel having one end affixed therein and having its other end projecting beyond said channel at the hinged

edge of the door for engagement with the door frame, a support for the said other end of the rod including a flat inclined bottom surface, said surface extending from a location adjacent the hinged edge of the door and being inclined downwardly therefrom toward the center of the rod, a closure strip disposed in said channel and movable therein to close the space beneath the door when the latter is closed, the edge at the top of said inclined surface of said support forming a line contact support for the said other end of said rod, and means suspending said strip from said rod so that the latter effects downward movement of the strip when the door is moved to closed position.
